UNITED STATES PATENT OFFICE

2,438,463

FLUID PRESSURE ACTUATED MOTOR

Ira J. Snader, Detroit, and Harold N. Seyferth, East Detroit, Mich., assignors to Ex-Cell-O Corporation, Detroit, Mich., a corporation of Michigan

Original application May 29, 1940, Serial No. 337,826, now Patent No. 2,350,372, dated June 6, 1944. Divided and this application June 9, 1943, Serial No. 490,150

11 Claims. (Cl. 121—38)

1
The invention relates to fluid pressure actuated motors and more particularly to motors of the piston and cylinder type especially well adapted for use in connection with machine tool elements, for example with such feed mechanisms for machine tools as that disclosed in our copending application Ser. No. 337,826 filed May 29, 1940 (now Patent No. 2,350,372) of which the present application is a division.

A general object of the invention is to provide a pressure fluid actuated motor embodying novel means for adjusting the operative movements thereof.

An object of the invention is to provide in a piston and cylinder type of pressure actuated motor novel means for varying the length of piston stroke with respect to a fixed or constant point within the range of piston movement.

More particularly stated another object is to provide in a motor of this type new and improved adjusting means which includes an abutment adjustable normally of the path of piston movement and variably engageable with the piston intermediate its ends in the movement thereof to limit the extent of piston travel equally or by predetermined amounts in each direction from the abutment.

Other objects and advantages will become apparent in the following description and from the accompanying drawings, in which:

Figure 1 is a plan view partly in section of a fluid pressure actuated motor embodying the features of the invention.

Fig. 2 is a side elevational view of the motor with certain parts thereof in vertical longitudinal cross section.

Fig. 3 is a vertical transverse sectional view through the motor and is taken along the lines 3—3 of Figs. 1 and 5.

Fig. 4 is a left-hand elevational view of the motor as seen in Fig. 2.

Fig. 5 is an elevational view on a reduced scale of the front portion of a machine apron or base with which the motor may be associated.

While the invention is susceptible of various modifications and alternative constructions, we have shown in the drawings and will herein describe in detail the preferred embodiment, but it is to be understood that we do not thereby intend to limit the invention to the specific form

disclosed, but intend to cover all modifications and alternative constructions falling within the spirit and scope of the invention as expressed in the appended claims.

5 The present invention will, for illustrative purposes be discussed as being a fluid pressure actuated motor for driving a machine tool element. In the drawings, therefore, the numeral 20 designates a portion of the base or apron of 10 a machine tool on which the motor is mounted and a shaft 21 represents a power take-off from the motor for connection with the machine tool element (not shown). By way of example, however, this element may be a feed screw actuated 15 from the shaft 21 through the combination of elements described and claimed in our parent application aforesaid.

The shaft 21 is adapted to be rocked or oscillated from a piston 22 in the fluid pressure 20 actuated motor by such a driving connection as a gear 23 on the shaft 21 engaged with a rack 24 on an intermediate portion of the piston.

In structures which embody elements driven by fluid pressure motors it may be desirable to 25 drive the element through a complete cycle by the movement of the piston in each direction or through each half of its reciprocatory cycle. It may also be desirable to produce identical movements of the element by each stroke of the piston 30 while variably adjusting the extent of such movements. Fluid pressure actuated motors embodying the present invention enable identical movements of the driven machine element to be produced by each movement of the piston and in all 35 operative variations of such piston movement.

Referring to Figs. 1 to 4, inclusive, the motor may be suitably supported, if mounted on a machine tool, by a shelf 25 extending horizontally from the inner face of the apron to which a motor housing 26 may be secured as by screws 27. Extending through a central portion of the housing is a bore 28 having its opposite ends closed by plates 29 (Fig. 2). The end portions of the bore form cylinders for the opposite ends 45 of the reciprocable piston 22.

In the upper face of the housing is a recess 30 of substantial size extending transversely of the housing in a direction normal to the bore 28. Grooves 31 (Fig. 2) in the upper margins of the recess 30 and cooperating gib strips 32 secured

to the housing provide ways for slidably receiving guides 33 on a block 34. The lower portion of the recess 30 intersects the upper portion of the bore 28. Beneath the bore 28 is a transverse bore 35 (see also Fig. 3) paralleling the recess 30 and intersecting the lower portion of the bore 28. Thus, the recess 30 and bore 35 intersect the cylinder bore 28 secantly respectively at diametrically opposite sides. The shaft 21 is rotatably mounted in the bore 35 and is suitably held against axial movement as by a shoulder at one end of the shaft and a nut and washer assembly 36 at the other end.

Means for adjusting the piston stroke is provided, which in the present instance is arranged to vary equally the permissible movement of the piston 22 in either direction from a fixed and constant point midway of its movement. Thus, the block 34 has on its lower face an abutment 37 of varying widths and preferably formed as an isosceles triangle. The abutment is disposed with its apex 38 entering a slot 39 formed between the ends of the upper portion of the piston 22 and with the apex of the abutment located on the mid-point of the travel of the piston. Shoulders 40 provided by the end walls of the slot 39 are angular with respect to the axis of the piston and a line normal thereto and preferably complement the angles of the opposing faces of the abutment.

Means is provided for adjusting the position of the abutment normally of the piston. Herein this means is a shaft 41 mounted for rotational but non-axial movement in a fixed part as by being journaled, as shown in Fig. 3, in a bore 42 in the apron 18 and held against relative axial movement by a collar 43 and a hand wheel 44 keyed, as at 45a, to the outer end of the shaft. The inner end of the shaft 41 is screw threaded for engagement with the block 34 whereby the operator's manipulation of the wheel 44 will adjust the position of the triangular abutment 37 with reference to the piston slot 39.

The end limits of the travel of the piston are, therefore, adjustable with respect to a fixed point located between the ends of the piston and the piston will travel equal distances beyond either side of such mid-point as designated in the instant structure by the apex of the triangular abutment. The length of the piston stroke may be adjusted by infinitesimal increments between a condition of full stroke, in which the triangular abutment is withdrawn to such position that it will not be engaged by the shoulders 40 on the piston, and a condition of no stroke in which the abutment is fully inserted into the slot and through engagement with both shoulders prevents movement of the piston.

Means may be provided for indicating to the operator the setting of the abutment with respect to the piston slot so that a stroke of any length and, consequently, any increment of movement of the machine tool element may be instantly reproduced. To this end the block 34 has an upstanding bracket 45 secured thereto as by screws 46. The bracket carries an elongated rod 47 fixed to extend parallel to the axis of shaft 41. In the illustrated structure the outer end of the rod extends through the apron and carries a series of graduations 48. A cooperating pointer 49 (Fig. 5) on the apron indicates the setting of the triangular abutment.

The end plates 29, closing the bore 28, are each tapped to connect respectively with fluid conduits

50 and 51 leading to any suitable source (not shown) of pressure fluid.

The present motor by virtue of the adjustability of the length of its stroke with reference to a mid-point of its travel which is constant or fixed for all conditions, is well adapted for use in environments where adjustment of the stroke with reference to an end or limit of its travel would be unsatisfactory. An example of the use 10 of our motor is in connection with the feed mechanism of a machine tool as described in the parent case above identified.

We claim as our invention:

1. In a pressure fluid actuated motor, the combination of a hydraulic cylinder having a piston 15 slidable therein, means for connecting the ends of said cylinder with a source of pressure fluid for moving said piston in opposite directions, and means for varying the extent of movement of said piston including longitudinally spaced shoulders on said piston, an angular abutment adjustably positioned between said shoulders and adapted for alternate engagement at opposite sides by said shoulders upon movement of said piston respectively in opposite directions, and means for shifting said abutment normally of said piston.

2. In a pressure fluid actuated motor, in combination, a hydraulic cylinder having a piston of 20 fixed length slidable therein, said cylinder having means for establishing the connection of its ends with reversible pressure fluid lines, and a single adjustable stop element adjustably coating with 25 said piston for varying the extent of movement of said piston in opposite directions with respect to a mid-point of such movement fixed for all variations thereof.

3. A pressure fluid actuated motor having, in combination, a cylinder, a piston reciprocable 30 therein, means for admitting pressure fluid alternately to the opposite ends of said cylinder, a longitudinal series of gear teeth along one side of said piston for connection with an element to be driven, said piston having in another side a recess providing longitudinally spaced opposed shoulders angularly related to the axis of said piston and to a line normal thereto, an abutment movable substantially normally of said piston and having side faces angularly related to the line 35 of such normal movement for engagement with said shoulders, said shoulders having an angularity complementary to that of said faces, and means for so moving said abutment.

4. A pressure fluid actuated motor having, in combination, a motor body having a cylinder bore 40 therein, an elongated piston reciprocable in said cylinder bore, means for conducting pressure fluid to opposite ends of said cylinder bore, said body having openings therein extending normally to and intersecting said cylinder bore on 45 opposite sides thereof intermediate its ends, a rotatable shaft in one of said openings, means for drivingly connecting said piston and shaft, a member slidably mounted in the other of said openings, means for adjustably moving said member, said piston having a recess therein intermediate its ends, means carried by said member extending into said recess, said last-mentioned means having surfaces thereon angular 50 with respect to the line of movement of said member, and shoulders on said piston complementary to said surfaces and defining the ends of said recess for engagement with said surfaces to limit the stroke of said piston.

5. In a pressure fluid actuated motor, the com-

bination of a hydraulic cylinder having an elongated double-acting piston of fixed length slideable therein, means for connecting said cylinder with a source of pressure fluid for effecting reciprocation of said piston, and a single adjustable abutment element engageable with the exterior of said piston between its opposite ends for variably limiting the extent of movement of said piston invariably to equal distances in either direction from a point substantially equidistant from the ends of said cylinder.

6. In a pressure fluid actuated motor, the combination of a hydraulic cylinder having a reciprocable piston therein, and adjustable wedge means with opposite inclined abutment surfaces engageable with said piston respectively upon movement of said piston in opposite directions to variably limit the stroke thereof equally and oppositely with respect to a fixed point intermediate the ends of such movement.

7. In a pressure fluid actuated motor, the combination of a hydraulic cylinder having an elongated piston reciprocable therein, longitudinally spaced shoulders on said piston and located intermediate the opposite ends thereof, an abutment member disposed for engagement with said shoulders alternately in the movement of said piston, said abutment member being of varying width, and means for adjustably positioning said abutment member to present portions of different width of said member for such engagement.

8. A pressure fluid actuated motor having, in combination, a motor body having a cylinder therein, a piston reversibly movable in said cylinder, means for directing pressure fluid alternately to opposite sides of said cylinder, said piston having a recess in one side thereof, means extending transversely of the piston axis into said recess and having oppositely facing surfaces thereon inclined with respect to the line of reciprocation of said piston, said piston having spaced shoulders complementary to said surfaces and defining the ends of said recess for engagement respectively with said surfaces to limit the stroke of said piston in each direction.

9. A pressure fluid actuated motor having, in combination, a motor body having a cylinder therein, a piston reciprocable in said cylinder, means for directing pressure fluid alternately to opposite sides of said cylinder, said piston having a recess therein intermediate its ends and defining oppositely disposed shoulders inclined equally in degree and oppositely relative to the line of reciprocation of said piston, and a wedge member extending transversely into said recess

and having oppositely facing surfaces thereon complementary to said shoulders and adapted for engagement respectively by said shoulders upon movement of said piston in opposite directions to limit the stroke of said piston equally in each direction.

10. A pressure fluid actuated motor having, in combination, a motor body having a cylinder bore therein, an elongated piston reciprocated in said cylinder bore, means for conducting fluid pressure to opposite ends of said bore, said body having openings therein extending normally to and intersecting said cylinder bore secantly respectively at diametrically opposite sides thereof, a 15 rotatable shaft in one of said openings, means for drivingly connecting said piston and shaft, a member slidably mounted in the other of said openings, said piston having a shoulder extending transversely of its line of movement, means 20 adjustably movable with said member and having a surface disposed in the path of said shoulder to limit the stroke of said piston in one direction, and means for adjustably moving said member.
11. A pressure fluid actuated motor having, in combination, a motor body having a fluid chamber therein, a pressure responsive member reversibly movable in said chamber, means for directing pressure fluid alternately to opposite sides of said chamber for effecting reversible 25 movement of said member, said member having a recess therein defining oppositely disposed shoulders inclined equally in degree and oppositely relative to the path of movement of said member, and a wedge member extending transversely 30 of said path of movement into said recess and having oppositely facing surfaces thereon complementary to said shoulders and adapted for engagement respectively by said shoulders upon movement of said member in opposite directions 35 to limit the stroke of said member equally in each direction.
